UNITED STATES PATENT OFFICE.

HORATIO C. HAWKS, OF NEWTON, MASSACHUSETTS.

ELECTRIC-LAMP FIXTURE.

1,070,463.

Specification of Letters Patent. Patented Aug. 19, 1913.

Application filed July 3, 1909. Serial No. 505,829.

To all whom it may concern:

Be it known that I, HORATIO C. HAWKS, a citizen of the United States, and a resident of Newton, in the county of Middlesex, 5 State of Massachusetts, have invented an Improvement in Electric-Lamp Fixtures, of which the following description, in connection with the accompanying drawings, is a specification, like letters on the drawings 10 representing like parts.

This invention relates to fixtures for electric lamps or the like, being more particularly intended to provide an improved reflecting attachment for use with incandescent lamps of high candle power for street 15 and public lighting, although the invention is not limited to this particular use.

The character of the invention may be best understood by reference to the following 20 description of an illustrative embodiment thereof shown in the accompanying drawing, wherein:

Figure 1 is a view partly in section and partly in elevation of the illustrative fixture embodying the invention; Fig. 2 is a bottom plan view of Fig. 1; and Fig. 3 is an enlarged sectional detail of parts shown in Fig. 1.

Referring to the drawings I have therein 30 shown a lamp fixture embodying one form of my invention, the same consisting of a reflector 3 of steel or other suitable material, having preferably a radially fluted, porcelain enameled or other suitably prepared 35 reflecting surface for the purpose of securing by reflection a wide and efficient distribution of light from the incandescent lamp 10. The flutes for the reflector herein shown are of a wide angled V-shaped cross section.

It has been found that, for a vertically arranged lamp, the widest and most efficient light distribution is obtained from a horizontal reflector having ribs or flutes substantially or closely approximating the horizontal. Heretofore, particularly for outdoor reflectors, this position of best efficiency has been departed from more or less, since it has been necessary to provide a pronounced dip or inclination from the center 45 toward the periphery of the reflector in order to permit water and accumulated ice or snow to drain off from the top of the reflector.

In the disclosed form of reflector there is 50 preserved a substantially horizontal position for the ribs or flutes, the top of the re- 55

flector being protected and drained by a protective hood 5 of galvanized steel or other suitable material having its surface convexed or inclined downwardly toward 60 its periphery to shed rain and prevent the accumulation of ice or snow on the top thereof.

In reflectors heretofore employed and particularly large size enameled reflectors, considerable trouble has been experienced from injury to the reflector or its enamel from handling the same and from injury after installation. This may be due to the cracking of the enamel owing to the vibration of the reflector, caused by a high wind, or other injury may be caused if the reflector is unprotected. In the inclosed form of reflector the latter is so supported and protected as to guard it against mutilation in handling, 75 and preventing, after its installation, any material vibration in one part of the reflector relative to another part thereof. For this purpose the flutings of the reflector terminate a short distance from the periphery 80 of the reflector to leave a flat rim 7. This permits the reflector to receive a substantially continuous support from the hood 5, the latter having its edge 8 lapped over the entire flat circumferential edge of the reflector so as to hold the latter securely in a groove 9 formed by the said lapped over edge. This provides a protecting rim for the enameled surface of the reflector and reduces any likelihood of mutilation in handling the same. At the same time it gives a continuous circumferential support to the reflector from the hood so that the edge of the former cannot be set into vibration by the wind and its enamel caused to crack 95 from such cause. Preferably the edge of the hood is pressed up securely to the edge of the reflector so that the latter is permanently and rigidly held by the hood, the combination of the inclined hood with the horizontal reflector circumferentially attached in this fashion providing a structure having great strength and adapted effectually to resist distortion or displacement of the hood relatively to the reflector.

Herein a lamp 10 of the tungsten type is used in connection with the reflector, it being understood, however, that other styles may be used as desired. The lamp is supported in any usual or suitable manner in a socket 11 which is inserted through a central aperture 13 in the reflector and is received by 100 105 110 115

an ordinary form of hollow cast iron canopy 15 which may be secured by set screws 17 to a flange 19 projecting upwardly from said hood. It will be seen that, while the fixture 5 as a whole receives the usual central support from the canopy, the reflector receives a continuous circumferential support from the hood.

In order to simplify the construction for 10 those cases where it is desired to employ a lamp guard, means are preferably provided for securing the lamp guard attachment or support directly to the reflector instead of to the lamp or its socket as has heretofore 15 been the practice, such construction as adopted in the illustrated embodiment also serving to strengthen the reflector. To this end the central portion of the reflector is cupped out to form a shouldered recess with 20 an upwardly extending flange 23 (Figs. 1 and 3), within which recess may be riveted or otherwise secured a threaded annular sleeve 25 of copper or other suitable material. The lamp guard 21 may then be 25 provided with a similar threaded sleeve 27 at its base by which it may be directly attached to the reflector or removed therefrom without in any way disturbing the lamp. By supporting the lamp guard directly on 30 the reflector the guard is rigidly held in place and is prevented from swinging about and chipping or otherwise mutilating the adjacent enameled surface of the reflector. The annular central flange 23 in the reflector 35 formed for the reception of the lamp guard attachment contributes also to the original rigidity and solidity of the reflector and hood.

It will be understood that several features 40 of my invention, while best adapted for combination with each other may be

used independently each of the other. It is also to be understood that this invention is not limited to the particular embodiment shown herein, nor to the particular purpose to which it is shown applied, but that its construction and adaptation may be varied within wide limits without departing from the spirit of the invention. ⁴⁵

Having thus described my invention, what I claim is: ⁵⁰

1. In a lamp fixture the combination of a lamp, a reflector therefor having a shouldered recess, a threaded ring rigidly secured in the recess and a lamp guard adapted to be screwed into said ring. ⁵⁵

2. In a lamp fixture, the combination with a reflector having an enameled fluted reflecting surface, a protecting hood to which said reflector is secured along its circumferential edge, said reflector having a central lamp receiving aperture and a lamp guard attachment rigidly secured to the reflector at said aperture, thereby strengthening the reflector thereat. ⁶⁰

3. In a lamp fixture, the combination of a reflector having a fluted enameled surface provided with substantially horizontal reflecting flutes terminating short of the circumferential edge thereof to leave a flat rim, and an inclined protecting hood for the top of the reflector having its circumferential edge lapped over and under said rim to protect the latter and hold the same securely in a groove formed by said lapped over edge. ⁶⁵ ⁷⁰

In testimony whereof, I have signed my name to this specification, in the presence of two subscribing witnesses. ⁷⁵
